UNITED STATES PATENT OFFICE

LESTER J. STEVENSON, OF CHICAGO, ILLINOIS

TELEPHONE SYSTEM

Application filed February 24, 1925. Serial No. 10,997.

This invention relates to improvements in telephone systems and has to do more particularly with the handling of calls between an exchange switchboard and a plurality of 5 subscribers' stations connected therewith.

The principal object of my invention is to provide an improved arrangement in connection with the exchange board whereby a call normally intended for any one of the 10 subscribers may under predetermined conditions be transferred and handled by an operator designated to attend to such calls, as, for instance, when the subscriber expects to be temporarily absent from his station and 15 wishes to have messages delivered to the calling party or have messages received from the calling party during his absence.

Other objects of invention will appear from time to time as the description proceeds.

My invention in its broadest aspect consists in the provision of a plurality of circuits auxiliary to the usual subscribers' circuits and provided with a manual switch and 25 a signal such as a lamp in such a manner that if the switch is closed the signal will be actuated by the same instrumentality used in calling the subscriber. In carrying out my invention, the signal and switch may be located either upon the usual switchboard so 30 that the regular switchboard operator can handle the call intended for the subscriber, or the signal and switch, together with an answering jack, may be located upon a special switchboard which, for convenience, may be called a "tell-tale" board, to be handled by a special operator, or the manual switch 35 may be located at one place, as, for instance, at a supervisor's desk, while the signal, together with an answering jack may be located on another switchboard to be handled by a tell-tale operator. The calling devices which operate the tell-tale signal may 40 consist in the usual ringing devices, such as the magneto or selective bell-ringing devices in a manual operator's cord-circuit, or 45 automatic ringing devices.

My invention may best be understood by reference to the accompanying drawings 50 showing its application in various ways to

switchboards of the common battery type. It will be understood to those familiar with the art, however, that it may be similarly applied to either single or multiple switch boards of the common-battery, magneto or 55 automatic type.

In the drawings,

Figure 1 shows the arrangement of my improved system as applied to an ordinary branch exchange switchboard and consists in connecting with the switchboard a separate tell-tale board having jack circuits in multiple with the subscriber's circuit on the main switchboard, and a remote control switchboard interposed between the two first named 60 boards for controlling the several multiple 65 circuits.

Figure 2 is an electrical wiring diagram showing one form in which each of the subscribers' circuits may be embodied. In this 70 form a special jack is provided to control the tell-tale circuit.

Figure 3 illustrates another form in which a standard jack of the two wire type is used, but in which a special relay is added to the 75 ordinary switchboard to operate the tell-tale circuit.

Figure 4 is still another form using a standard double circuit jack, but in which another form of relay is used in the tell-tale 80 circuit.

Figure 5 is a view showing the arrangement of an ordinary branch exchange switchboard and a tell-tale switchboard similar to Figure 1, but in which the tell-tale switch 85 devices are incorporated in the tell-tale switch board.

Figure 6 is a diagrammatic view illustrating a form of circuit in which the switch is incorporated on the tell-tale switchboard as 90 shown in Figure 5.

Figure 7 is a view showing one manner in which the tell-tale circuits may be incorporated in the regular branch exchange switchboard, this board being termed for 95 convenience a "double duty" board.

Figure 8 is a diagrammatic view of one form of circuit which may be employed in the double-duty board shown in Figure 7.

Figure 9 is a circuit similar to Figure 8, 100

but in which another arrangement of signals is provided.

Figure 10 is a view showing a switch arrangement applicable to the forms shown in Figures 8, 9, or 10, to permit one audible signal to serve all the subscribers' circuits.

Figure 11 is a view showing another arrangement of tell-tale switches incorporated in the main switchboard with the tell-tale switch adjacent its corresponding jack.

Figure 12 is another form of circuit in which the tell-tale signal is operated by being placed in series with the through circuit signal in the operator's cord circuit.

Figure 13 is a view similar to Fig. 12, but including a relay in the tell-tale circuit to give full voltage on the tell-tale signal.

Referring now to details shown in the drawings, Figure 1 shows a typical installation of my invention as applied to an ordinary exchange switchboard 10, provided with a plurality of subscribers' jacks 11 and associated signals 12 in the usual manner. For convenience, only one of the jacks and signals are illustrated, it being understood that the face of the board is provided with a plurality of similar devices, each serving one of the subscriber's lines served by the board. The board is also provided with the usual operating cord circuits and operator's equipment, including listening-in and ringing devices and trunk line connections, which need not be shown or described in detail as they form no part of the present invention.

I have chosen to show a signal device of the lamp type such as is commonly used with common-battery switchboards, but it will be understood that any other signal device such as the shutter type may be used with equal facility. A second board 15, which for convenience I refer to as the "tell-tale" board is provided with a plurality of jacks 16 and associate signals 17 corresponding with the number of subscribers' circuits served by the main switchboard 10 and each of the corresponding jacks and signals being connected by separate circuits, which connection, as illustrated in the forms shown in Figures 2, 3, and 4, hereinafter to be described in detail.

may consist of three conductor wires 18, 19 and 20. One of the conductor wires such as the upper wire 18, passes through an intermediate control board 25, which I prefer to call a "remote control switchboard". This board is provided with a series of manually operated switches 26, each inserted in one of the connecting lines 18 between corresponding subscribers' jacks and tell-tale signals

on the two switchboards 10 and 15 respectively. Inasmuch as each of these switches 26 consist of simple contacting devices of any suitable construction, they may be mounted in compact arrangement so that the remote control board 25 as shown is considerably

smaller than the other switchboards 10 and 15.

Referring now to the circuit shown in Figure 2 illustrating the use of my invention in connection with the ordinary two-wire common-battery system, the subscriber's circuit is shown in the usual diagrammatic form consisting of a transmitter 30, receiver 31, phone condenser 32, induction coil 33, bell 35, condenser 36 and main subscribers' lines 40 and 41, leading to the subscriber's jack indicated generally at 42. The jack is provided with a pair of spring contacts 43 and 44 adapted to be engaged by the plug inserted through the thimble 45 in the usual manner. The upper spring contact 43 is connected to the main line 40 leading from the subscriber's station, while the lower spring contact 44 is connected to the other conductor 41 of the subscriber's circuit. The usual line signals are provided on the main switch board in connection with each of the jacks. In the form shown a line lamp 12 with a relay 54 is provided, including a pair of contacts 50 and 51, the upper contact 50 of which leads to ground through connection 52 while lower contact leads through conductor 53 of line relay 54 and battery 55 of ground 56; the relay 54 serving to control the local circuit containing the line lamp 12 and pilot relay 61 which relay in turn controls the local circuit including a pilot lamp 62 of the usual form.

The equipment on the tell-tale board 15 consists of a simple jack 16 having an upper and lower spring contacts 71 and 72 connected in multiple with the subscriber's line, in the present instance being in parallel across the corresponding spring contacts 43 and 44 of the main switchboard jack 42. The signal device 17 of the tell-tale board which in the form illustrated is a line lamp, is connected in the circuit including a contact 75 incorporated in and controlled by the operation of the main jack 42, so as to be closed when the plug is inserted in said jack. One side of this switch is grounded as shown and the other side is connected through the switch 26 on the remote control board as shown in Figure 1 and from thence through the signal lamp 17 and a pilot relay 76 controlling the pilot lamp 77 on the remote control board. In the form illustrated in Figure 2, above described, it will be observed that the jack 42 is of special construction including the contact 75. The tell-tale board is also furnished with the usual cord circuits and operator's listening equipment similar to the equipment on the main board 10.

The use and operation of the apparatus above described in connection with Figures 1 and 2 is as follows: Assuming that the main exchange board 10 is located in a large establishment, such as a hotel, it is provided with subscribers' circuits serving each of the rooms

in the hotel. This board is located in the usual position, as, for instance, in the lobby of the hotel and served by the usual telephone operator. The tell-tale board 15 may be located adjacent the main board 10 or at any other convenient place in the hotel building where space is available. The remote control switchboard 25 is preferably located at the main clerk's desk or a special clerk's desk, where it is readily accessible to such hotel guests as may desire to avail themselves of the tell-tale service.

If the occupant of the room served by the subscriber's circuit represented by jack 11 and line lamp 12 on the main board 10 is in his room and a call is received by the main switchboard operator, the latter plugs in on this subscriber's circuit and the bell rings in the guest's room in the usual manner. If the switch 26 on the remote control switchboard 25 is open, the line lamp 17 corresponding to this guest's room on the tell tale board is dead, so that no action as to this subscriber's circuit is required of the tell-tale operator. However, if the occupant of the room wishes to leave his room to go some other place in the hotel or to leave the hotel, he phones, or goes to the clerk or other person at the remote control switchboard and advises him of his plans, either verbally or by leaving a written statement. Further, if he wishes to leave any message for a party calling him in his absence, he may make such a statement or write the message accordingly. The remote control operator then closes the switch 26 corresponding to this guest's room number and sends the guest's message to the tell-tale operator at the tell-tale board 15, either by telephone or by messenger. When the switch 26 is closed it is obvious that any call received on the main switchboard 10 directed to this guest's room will be plugged in by the main operator and the telephone in the guest's room will ring in the usual manner. At the same time, however, since the circuit through the signal line 18 is closed at switch 26, the line lamp circuit on the tell-tale board will be energized so as to flash the line signal to 17 on the latter board to tell the tell-tale operator. She will then plug in with her cord circuit and listening key in the usual manner and talk with the calling party, advising this party of any messages which have been left by the absent party if called, and to take any messages which the calling party may wish to leave. It will be observed that the signal to the tell-tale operator is accomplished without interrupting in any manner with the usual operation of the main switchboard by its operator, since she plugs in and rings the subscriber's room in the usual routine manner, but the call is answered by the tell-tale operator instead of by the subscriber. When the tell-tale operator answers the call her cord circuit completes the talking circuit

in parallel with the subscriber's circuit with the result that so far as the main operator at switchboard 10 is aware the subscriber himself has answered and is talking on his line. Therefore, in my improved system the operation of the tell-tale board and switch mechanism is entirely independent of the operation of the main switchboard 10 and relieves the operator of the switchboard from answering for the guest after the guest fails to reply, and furthermore, saves the calling party the long wait to ascertain whether or not the guest is going to answer his phone. In fact, the tell-tale system immediately places the calling party in contact with the tell-tale operator who is in a position to give him the proper information in the shortest possible time. Many other advantages will be hereinafter described in greater detail.

While the above example of the operation of my improved apparatus is described in connection with the operation of hotel switchboards it will be understood that the apparatus is adapted to any form of telephone service embodying a switchboard serving a plurality of single or multi-party subscriber lines.

In the form shown in Figure 3, an arrangement of parts is shown similar to that in Figure 2, excepting that a standard jack of the two-wire type is employed. In this instance, the circuit for operating the signal 17 on the tell-tale switchboard is provided by means of a separate relay 80 of high resistance connected across the subscriber's lines 40 and 41 and adapted to be actuated in the bell ringing current in the subscriber's circuit so as to close the contact 81 of the relay to complete the circuit through the line lamp 17 whenever the subscriber's bell ringing current is applied from the cord circuit by the operator at the main switchboard 10.

Figure 4 is a view similar to Figure 3, but in which the contact of the line lamp 17 on the telltale board is controlled through a low resistance relay 82 in series with one of the conductor wires such as wire 40 of the subscriber's circuit and also actuated by the bell-ringing current from the operator's cord circuit on the main switchboard 10.

Referring now to the form shown in Figures 5 and 6 in which the remote control board 25 is dispensed with, it will be observed that the switches 87, corresponding to remote control line switches 26 in Figs. 1 to 4, inclusive, are incorporated in the tell-tale switch board 15^a itself, and in connection with each jack 16 and its corresponding signal 17^a. In the form shown the switches 87 for each subscriber's circuit is placed immediately below its associated jack 16^a, but obviously this switch may be placed in any other suitable place adjacent its jack and signal. The circuit for this arrangement may be substantially the same as shown

in Figures 2, 3, or 4, excepting that the switch 87 in line 18^a is placed directly on the tell-tale switchboard 15 instead of in an intermediate position. In the form shown in Figure 6 the switch 87 consists of a single contact type having a spring 85, normally out of engagement with an anvil 86 but which may be depressed by the turning of a suitable switchkey of the usual form.

My invention may also be applied in modified form directly to the main exchange switchboard, so that the regular switchboard operator may give tell-tale service in addition to her regular duties in controlling the board. Obviously this type of service does not present all the advantages obtained where a separate tell-tale board is provided to relieve the regular operator of all details of tell-tale service. A double duty board 90 as shown in Figure 7 may, however, be used in connection with a relatively small switchboard receiving such a small number of calls that the regular operator will have time to attend to the tell-tale service. In this instance, my invention consists in providing a means of selectively setting the subscribers' lines by means of a manual switch so as to automatically inform the regular operator that the particular line is set for tell-tale service.

In the form of board shown in Figure 7 a small switch board 91 is added at one side of the main board, this small board being provided with a plurality of tell-tale switches 92 each connected with the usual subscriber's circuit on the main board, including jack 93 and signal 94. A typical circuit for this arrangement is shown in Figure 8. This form of board differs from the simple combination of a tell-tale switch board 15 and main board 10 and shown in Figure 5, in that the usual tell-tale jack in multiple with the subscriber's circuit may be eliminated, as well as the line lamp 17^a in the tell tale circuit. The separate tell-tale jack may be eliminated entirely since the signal operator can use her cord circuit for talking with the calling party. The tell tale signal 17^a which in the form shown in Figures 1 and 5 is flashed on the separate board, may be substituted by a signal operative on the main board in connection with the called circuit signal. Such an arrangement is shown in detail in Figure 8 in which the subscriber's circuit and plug are of the usual form, but in addition, the tell-tale switch 92 is provided on the board 93 in circuit with an audible tell-tale signal 95 in parallel with the subscriber's circuit through conductors 96 and 97, so that when the switch 92 is closed, the tell-tale signal is operated by the ringing current applied by the operator in the usual manner through her cord circuit. With this arrangement, whenever the operator inserts her calling plug in a subscriber's jack the tell-tale circuit of which has previ-

ously been closed by its respective tell-tale switch 92, she will be automatically advised of the fact that this particular line has been set for tell-tale service by the ringing of the audible signal 95 when she rings the subscriber's station in the usual way. This diagram also shows another means of signalling the operator for tell-tale service, comprising a conductor 97 and relay 98 for operating another relay circuit controlling the usual line signal 17. This line signal 17 is provided with the usual calling relay 54, arranged to disconnect the line signal when the operator plugs in on the subscriber's jack. In the present form, however, the circuit controlled by the relay 98 and actuated by the bell ringing current passes through conductors 99, 100 and 101 to light the line signal 17 whenever the tell-tale switch 92 is closed. In this manner the operator gets the flash of the lamp 17 to indicate that the particular subscriber's tell-tale switch has been set. Obviously, the audible signal 95 and the line signal 17 may be used, either in conjunction with each other, or may be used separately, if desired. For example, Figure 9 shows a simplified arrangement in which the relay for actuating the line lamp by the bell ringing current is omitted.

Figure 10 is a view illustrating the manner in which a single tell-tale signal on the double duty switchboard 90 may be used to serve a plurality of subscribers' lines, each comprising conductors 40 and 41. One side of said subscribers' lines, such as conductors 40 are each connected to one of the tell-tale switch lines 18, 18, leading to one side of separate tell-tale switches 92, 92, the other side of said switches having common connection through signal 95 and conductor 105 to the other conductor 41 of all of the subscribers' lines. In this manner a single audible signal may be used to serve all of the subscribers' stations on a double duty switchboard as illustrated in Figures 7, 8 and 9.

In the form shown in Figure 11, the tell-tale switch is incorporated directly upon the double duty board. The subscriber's jack shown in this figure is provided with the usual line signal 17 and line signal relay 54 operative so that the line signal flashes when the subscriber is calling, but is discontinued in the usual manner, as soon as the operator inserts her answering plug. In addition to this equipment, I provide a tell-tale signal circuit, including a tell-tale switch contact 109 which is depressed, when closed, so that when the calling plug is inserted in the subscriber's jack, another circuit is completed through the line signal 17, traced as follows: line battery 55, line signal 17, anvil 111, contact 109, conductor 112, anvil 113, jack contact 114, and ground line 115, so as to cause the line signal 17 to continue to burn after the calling plug is inserted in the jack.

Figure 12 illustrates another method which may be used in connection with three-wire switchboard systems, in which the jack thimble 110 is grounded. In this instance, the 5 conductor 18^a leading to the tell-tale line signal 17^b is connected to the thimble 110, but is provided with an intermediate two-way switch 26^b, which may be manually controlled to complete a circuit through the operator's cord circuit plug 111 and circuit 112 direct to ground through a grounded cut-off 113, or through the tell-tale line signal 17^b. This arrangement may be applied either to a separate tell-tale board system or to a double-duty board. In the latter instance it may be convenient to provide an operator's signal in the cord circuit, by means of a lamp 115 which may be one of the usual through-circuit-signals added to the cord circuit. If desired, the tell-tale line 18^a may also be provided with an operating relay 116 and line battery 117, as shown in Figure 13.

From the above description of several simplified arrangements for producing the tell-tale signal and answering circuits, it will be manifest that many other modifications of my invention will readily suggest themselves to anyone skilled in the art. I do not therefore wish to be understood to be limited to the exact constructions shown and described, excepting as defined in the following claims.

I claim:

1. A telephone system comprising an exchange switchboard provided with a plurality of separate circuits for individual subscribers, and each having an answering jack, a cord circuit including a calling apparatus for said subscribers' circuits, and trunk lines therefor, and an auxiliary circuit including an independent control device and a signal connected with each of said subscriber's circuits, whereby the signal is automatically actuated by the calling apparatus effective in each of the subscriber's circuits when the corresponding control device is set in a predetermined position, and an answering jack adjacent said auxiliary signal and in parallel with the corresponding answering jack on the exchange switchboard.
2. A telephone system comprising an exchange switchboard provided with a plurality of separate circuits for individual subscribers, and each having an answering jack, a cord circuit including a calling apparatus for said subscribers' circuits, and trunk lines therefor, and an auxiliary circuit including an independent control device and a signal connected with each of said subscriber's circuits and adapted to be automatically actuated by the calling apparatus effective in each of the subscriber's circuits when the corresponding control device is set in a predetermined position, and an auxiliary answering jack adjacent each of said auxiliary signals and in parallel with the corresponding answering jack on the exchange switchboard.

on the switchboard, said auxiliary answering jacks and signals being mounted on a board separate from the main switchboard.

3. A telephone system comprising an exchange switchboard equipment including a plurality of subscriber's circuits each having an answering jack, and calling apparatus therefor, and an auxiliary circuit including a control device and a signal connected with each of said subscriber's circuits and adapted to be automatically actuated by the calling apparatus effective in each of the subscriber's circuits when the corresponding control device is set in a predetermined position, and an auxiliary jack adjacent each of said auxiliary signals and in parallel with the corresponding answering jack on the switchboard, said auxiliary answering jacks and signals being mounted on a board separate from the main switchboard, and the control devices being interposed in a separate group between the main switchboard and the auxiliary switchboard.

4. A telephone system comprising an exchange switchboard equipment including a plurality of subscriber's circuits each having an answering jack, and calling apparatus therefor, and an auxiliary circuit including a manual switch and a signal connected with each of said subscriber's circuits and adapted to be automatically actuated by the calling apparatus effective in each of the subscriber's circuits when the corresponding manual switch is in closed position, and an auxiliary answering jack adjacent each of said auxiliary signals and in parallel with the corresponding answering jack on the switchboard, said auxiliary answering jacks and signals being mounted on a board separate from the main switchboard, and the manual switch devices being interposed in a separate group between the main switchboard and the auxiliary switchboard.

5. An office building telephone service system, comprising an incoming telephone line, a telephone set connected thereto in a tenant's office, a line from said telephone set to an outlet in a central switchboard, identifying means adjacent said outlet, and switch means operable from said tenant's office to route an incoming call directly to the central switchboard, or to the telephone set in the office of the tenant, at will.

Signed at Chicago, Ill., this 18th day of February, 1925.

LESTER J. STEVENSON.
